UNITED STATES PATENT OFFICE.

RICHARD H. WYMAN, OF EVANSTON, ILLINOIS.

INDEX.

SPECIFICATION forming part of Letters Patent No. 323,484, dated August 4, 1885

Application filed September 16, 1884. (No model.)

To all whom it may concern.

Be it known that I, RICHARD H. WYMAN, of Evanston, in the county of Cook and State of Illinois, have invented a new and Improved 5 Index, of which the following is a description, reference being had to the accompanying drawing, in which the figure is a perspective view of a blank-book containing said index.

The object of my invention is to provide an 10 index or key adapted to be used in connection with the ordinary "sight" or marginal index employed in blank-books, and which may be especially applicable to letter-books, the use of which said key may enable one to refer at 15 once to a letter of any given date without being obliged to search at random therefor, as has heretofore been necessary in case of extensive correspondence. A further object is to enable the user to determine at once to what 20 extent said book has been posted or indexed, all of which will be hereinafter more fully described and definitely pointed out in the claims.

A in the drawing represents an ordinary blank letter-book, in the front portion of which 25 are the usual index-pages, *a a*, having arranged upon their margin, in the usual manner, the customary sight-index letter, *a*. The pages *a* are preferably shortened at the top, as clearly shown in the drawing, and an extra leaf, B, 30 is inserted between them and the first page of the numbered blank pages, said leaf being of the full size of the book. That portion of the leaf B shown above the index-leaves *a* is divided into spaces by horizontal and vertical lines, substantially as shown, the width of 35 the vertical spaces being governed, as herein-after shown, by the number of pages in the book. The left-hand vertical column contains the words "Page," "Day," and "Month," respectively, while each vertical column there- 40 after is intended to represent one day, and serves as a key of reference to the letters copied in said book for that day. At the end of the day, after all the letters are copied in the book for that day, the names of those to 45 whom they are addressed are indexed in the usual manner upon the pages *a*, with the numbers, respectively, of the pages upon which they appear. The number of the 50 last page used is then placed in the lower

space of one of said vertical columns marked "Page" in the margin, while the date is indicated by two figures in the respective spaces above. Assuming, for example, that an extensive correspondence is being carried 55 on with A. H. Hall, and one is desirous of consulting a letter to him of February 8, if the page-numbers on the page *a* are numerous, it would be necessary to examine each page successively in order to find the required 60 letter; but, upon reference to the key, he finds that the letters copied on that date (indicated by the figures 2 and 8, respectively) extend from page 90 to page 114. Referring to the index, he sees that but one number within 65 that range appears after the name given—viz., 106—and hence he is enabled to refer to the proper page at once, regardless of what other numbers may appear upon the index-page *a*. Other examples might be given, but this is 70 deemed sufficient to illustrate the principle. A further advantage of said key is that it enables one to determine at a glance the extent to which said letter-book has been posted or indexed. Assuming the book to show the 75 names and figures given in the drawing, and that letters are copied upon two hundred pages of said book, the writer would know at once that eighty-six pages had not been posted, and that the last letter indexed was written on 80 February 8, and copied on page 114. Should the number of pages in the book be unusually 85 large, and the correspondence moderate, it is obvious that a larger number of vertical spaces may be needed, in which event said index-pages may be made still shorter, and said key continued in like manner at the bottom, of the page, or at the top below that shown; but I should prefer to place it at the bottom to avoid possible confusion. Instead of said 90 key being placed upon a separate leaf, it may be upon a continuation of the last index-leaf, which may, if preferred, be made the full size of the book, or all the index-pages may be of full size, and the key placed upon a sep- 95 arate leaf immediately preceding or following said index without varying the essential principle of my invention. Should said index-leaves be shortened or cut off at the top or bottom, or both, one or more pads or blocks, 100

e, of paper, of the thickness of said initial sheets, may be glued or otherwise secured to the cover of the book A, as shown, to compensate for the thickness of said index-sheets, 5 so that in taking an impression the letters or bills may be copied equally well over the entire page.

It is obvious that said index may be used with equal facility and advantage in bill-
10 books as well as in letter-books.

Having thus described my invention, I
claim—

1. As a new article of manufacture, a blank letter or impression copying book provided
15 with the usual marginal or sight index, the pages of which latter are made smaller than

those of the book to permit a page containing a key constructed as described to protrude from beneath or extend beyond the same, substantially in the manner and for the purposes 20 specified.

2. The combination of the key arranged as specified with the shortened initial marginal index-pages of a blank-book, and a pad to compensate for the portion of said index-pages 25 cut off, substantially as and for the purposes specified.

RICHARD H. WYMAN.
